(57) **CLAIM**

The ornamental design for a car washing gun, as shown and described.

DESCRIPTION

FIG. 1 is a front elevation view of a car washing gun showing the new design;

FIG. 2 is a back elevation view thereof;

FIG. 3 is a left-side view thereof;

FIG. 4 is a right-side view thereof;

FIG. 5 is a top plan view thereof;

FIG. 6 is a bottom plan view thereof;

FIG. 7 is a perspective view thereof;

FIG. 8 is another perspective view thereof;

FIG. 9 is an enlarged view of the encircled portion in FIG. 3;

FIG. 10 is an enlarged view of the encircled portion in FIG. 7;

FIG. 11 is an enlarged view of the encircled portion in FIG. 8; and,

FIG. 12 is an enlarged view of the encircled portion in FIG. 8.

The broken lines depict portions of the car washing gun that form no part of the claimed design.

The dash-dot lines in FIGS. 3, 7, 8, 9, 10, 11, and 12 illustrate the boundaries of the enlarged view indicators and form no part of the claimed design.

1 Claim, 12 Drawing Sheets
